UNITED STATES PATENT OFFICE

HARRY RASKIN, OF NEW YORK, N. Y.

DESIGN FOR A VEHICLE RADIATOR GUARD

Application filed September 15, 1930. Serial No. 36,968. Term of patent 7 years.

To all whom it may concern:

Be it known that I, HARRY RASKIN, residing at New York, county and State of New York, have invented a new, original, and ornamental Design for Vehicle Radiator Guard, of which the following is a specification, reference being had to the accompanying drawings, forming part thereof.

In the drawings, Fig. 1 is a perspective view of a vehicle radiator guard showing my new design, and

Fig. 2 is a side view of the vehicle radiator guard, according to my new design.

I claim:

The ornamental design for a vehicle radiator guard as shown.

In testimony whereof I hereunto affix my signature.

HARRY RASKIN.
